(57) **CLAIM**

The ornamental design for the bed frame, as shown and described.

DESCRIPTION

FIG. 1 is a front elevational view of a bed frame, incorporating the design of my invention;

FIG. 2 is a left side elevational view thereof;

FIG. 3 is a rear elevational view thereof;

FIG. 4 is a right-side elevational view thereof;

FIG. 5 is a top plan view thereof;

FIG. 6 is a bottom plan view thereof;

FIG. 7 is a vertical, cross-sectional view along Line 7—7 of FIG. 2, depicting the front of the headboard;

FIG. 8 is a vertical, cross-sectional view along Line 8—8 of FIG. 2, depicting the rear of the footboard; and,

FIG. 9 is a vertical, cross-sectional view along Line 9—9 of FIG. 1, depicting the surface contours of the front and rear surfaces of the central panel of the headboard and footboard of the bed frame and the inner surface of the right side.
